(57) **CLAIM**

The ornamental design for a microfluidic device for biological analysis, as shown and described.

DESCRIPTION

FIG. 1 is a top perspective view of a microfluidic device for biological analysis in accordance with the present design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines, the area within them, and the areas bounded by broken lines and solid lines are included for the purpose of showing environmental structure or boundary lines that forms no part of the claimed design.
